Specification for Design.

Patented July 4, 1916.

Application filed October 18, 1915. Serial No. 56,622. Term of patent 3½ years.

To all whom it may concern:

Be it known that I, MAIMON SAMUELS, a citizen of the United States, and a resident of Seattle, in the county of King and State of Washington, have invented a new, original, and ornamental Design for a Surgical Instrument, of which the following is a specification, reference being had to the accompanying drawing, forming a part thereof.

In the drawings, Figure 1 is a face elevation of my surgical instrument. Fig. 2 is a side elevation of same. Fig. 3 is a cross sectional plan of the central portion of my surgical instrument.

I claim:

The ornamental design for a surgical instrument as shown.

MAIMON SAMUELS.
